UNITED STATES PATENT OFFICE

2,466,000

PHOTOPHONE

Chester L. Brown, Spokane, Wash.

Application June 12, 1945, Serial No. 599,008

5 Claims. (Cl. 250—7)

1

The present invention relates to certain new and useful improvements in a photophone and affords a compact device wherein the transmitter and its power source are housed in a conventional 5-cell flashlight case; and the receiver is likewise housed in a similar flashlight case, the two flashlight cases being slidably and rotatably mounted on an expansible clamp which enables the transmitter and the receiver to be brought into the proper mouth and ear positions.

According to the present invention, the audio wave is carried on a light beam derived from a filament lamp of the flashlight type and this filament is modulated by the audio current variations produced by the microphone which is connected direct to the transformer without resorting to any intervening amplifier.

The invention is particularly directed to certain structural arrangements which afford a compact transmitter and receiver unit which can readily be carried about in constant readiness for instant use where two persons each equipped with the invention and in sight of each other, have need for two-way photophone communication. It is particularly serviceable for roof-to-ground conversation by city fire departments. It serves a similar purpose during construction of buildings. It is likewise serviceable for directing workers from a distance such as in excavations, or in bridge building, or in mines, quarries, etc.

The preferred form of the invention is shown in the accompanying drawings.

Fig. 1 is a sectional view of the transmitter and receiver coupled together by an expansible clamp.

Fig. 2 is a wiring diagram of the transmitter shown in Fig. 1.

Fig. 3 is a plan view of the invention showing the transmitter and receiver slidably moved to their operating positions and spaced apart by expanding their connecting clamp.

Fig. 4 is a wiring diagram of the receiver shown in Fig. 1.

The transmitter is shown in Fig. 1 and Fig. 2 where it will be seen that the secondary *f* of the transformer **6** is connected in series between the lamp **2** and battery **S**, and the primary *g* of this transformer **6** is connected in series between the microphone **12** and battery **S**. The switch **X**

2

is interposed between the battery and ground which is common to the lamp **2** and microphone **12**.

Thus it will be seen that the D. C. current from the battery **S** passes through the secondary *f* to the lamp **2**, and the A. C. current which is induced in the secondary *f* also flows to the lamp **2** to modulate the light therefrom in accordance with the audio current variations produced by the microphone **12**. The primary *g* is made to match the impedance of the microphone; and the secondary *f* is made to match the impedance of the filament of the lamp **2**. This impedance matching transformer **6** is fully sufficient to satisfactorily modulate the light emitted by the lamp **2** and no intervening amplifier is necessary.

Fig. 1 shows the physical embodiment of this transmitter, when housed in the 5-cell flashlight case **Y** which is the preferred embodiment. The transformer **6** occupies the position which would normally be occupied by the forward battery, and only four batteries are used. Here the lamp **2** is mounted in a socket **3** which has its shell connected to the casing **Y** which here serves as ground, and the center contact connects to the secondary *f* of the transformer **6** which is here shown in diagram in the space which it occupies in the flashlight case **Y**. A spacer member **8** is provided with a central contact member **7** to which the secondary *f* is connected as is also the primary *g*. This contact member **7** extends through the spacer member **8** so as to afford contact with the positive pole of the battery **S''**. The remaining batteries are arranged end to end in series, and the last battery **S** contacts a spring **11** which is mounted on the insulator **10**. The line **14** connects this spring **11** to the insulated side of the switch **X**.

The microphone **12** is of the single button carbon granule type. As shown in Fig. 1 this microphone **12** is secured to the closure **16** which is threaded onto the flashlight case **Y** thus affording the necessary ground connection. The central button seats against a contact **9** in the insulator **10** and the line **15** connects this contact **9** with the primary *g* of the transformer **6**. The spring **11** bears against the battery **S** and maintains the necessary contact, but unlike the usual flashlight, the spring **11** does not connect the negative pole of the battery **S** to ground, the line

14 and switch X are here used to establish that ground connection, so that this one switch closes the circuit for the microphone at the same time the lamp circuit is closed.

It will be noted that the outer ends of the wires 14 and 15 connect to the insulator disc 10 and there is sufficient slack in these wires to enable this insulator disc 10 to be lifted out whenever the microphone 12 is removed for the purpose of installing new batteries.

The lamp 2 is here shown with a reflector 4 and a plano glass 5; however, a convex lens may be used if desired. It is necessary however that the emergent beam be sufficiently divergent to form an illuminated area 12 or 15 feet in diameter at a distance of 100 yards, so that simple pointing of the transmitter will suffice, without resorting to any sighting means.

The receiver portion of the invention is mounted in the flashlight tube Z as shown in Fig. 1 and the circuit diagram is shown in Fig. 4.

These flashlight tubes are conventionally made with an expanded portion W which is threaded so as to attach the forward end of the casing. This expanded portion is conventionally of sufficient size to admit the photoelectric cell M which is of the cartridge type such as R. C. A. 921.

The receiver is a three tube, resistance coupled amplifier and is carried on a chassis 21 which has brackets such as b secured thereto for mounting the tubes V in end to end relation, and an end bracket d is provided for mounting a jack 44 for connecting the receiver to its power source. This chassis 21 is transversely cupped so as to suitably fit within the tubular casing Y. This transverse cupping may be arcuate or else angular, either of which will suffice to stiffen the chassis longitudinally, as well as afford a proper fit within the casing. The forward end of the chassis has a slotted end 22 which is offset to correspond to the expanded portion W. This slotted end 22 is to accommodate the seal-off tip conventional on this type of photoelectric cell M, the usual protector cap being discarded. This structure affords the necessary contact of the cathode 20 to ground. A plate member 18 is employed to connect the anode 19 to the receiver circuit, a suitable insulator 17 being employed to prevent grounding the anode.

For convenience of illustrating the end to end relationship of the amplifier tubes, the circuits are pictorially shown in Fig. 1 where the conventional seven contact base has the 4th and 5th contacts cut off, and the 6th and 7th contacts are shaded to indicate that they are on the far side from the 1st, 2nd and 3rd contacts. The 1st contact is here shown as bent over for convenience of connecting to the positive A voltage line. From this description the various contacts can readily be identified, and it is of course well known that the 1st and the (shaded) 7th contacts go to the two sides of the filament, the 2nd contact goes to the anode, the 3rd contact goes to the 2nd grid, and the (shaded) 6th contact goes to the 1st grid. It is of course well known that the 4th and 5th contacts are not needed for an IT4 vacuum tube such as here used. With this understanding, the circuits can readily be followed in Fig. 1 equally as well as in the diagram of Fig. 4.

The condenser E couples the anode 19 to the control grid of the first amplifier. The resistor 23 connects this same control grid to ground.

The positive A voltage from the battery 47 is fed from the jack 44 through the line 25 to the filament of each of the amplifiers, the opposite

side of each filament being connected to ground as shown. The positive B voltage from the battery 47 is fed from the jack 44 through the line 41 to each of the amplifier tubes and to the photoelectric cell. The anode 19 is connected to the +B line 41 through the load resistor 26 and decoupling resistor 27, the latter being by-passed to ground by the decoupling condenser F so as to isolate the photoelectric cell M from the last amplifier stage.

Resistor 28 connects the screen grid of the first amplifier to the +B line 41. This screen grid is by-passed to ground by the condenser H. The plate of the first amplifier tube, is connected to the +B line 41 by the load resistor 29 and decoupling resistor 30, the latter being by-passed to ground by condenser K. The condenser G couples the output of the first amplifier tube to the control grid of the second amplifier, and this control grid is connected to ground by the resistor 31.

The plate of the second amplifier is connected to the +B line 41 through load resistor 33 and decoupling resistor 34 the latter being by-passed to ground by the condenser R so as to isolate this amplifier from the final amplifier stage. Resistor 32 connects the screen grid of this second amplifier to the +B line 41. This screen grid is by-passed to ground by condenser P. The condenser N couples the output of this second amplifier to the control grid of the final amplifier, and this control grid is connected to ground by the resistor 35 and also by-passed to ground by the condenser I which eliminates the high audio frequencies.

The plate of the final amplifier is connected to the +B line 41 through load resistor 37. The resistor 36 connects the screen grid of this final amplifier to +B line 41 and this screen grid is by-passed to ground by condenser U. The condenser T couples the output of this final amplifier to the earphone 39, the plug 42 and jack 43 being employed for convenience of removing the assembled receiver from the flashlight casing Z. The earphone 39 is mounted upon the casing by brackets 38 and suitably grounded to the casing as indicated at 40.

As seen in Fig. 1, this three stage amplifier can readily be housed in a flashlight casing of the same size as that previously described for housing the transmitter, and as here shown, the convex lens L is employed to condense the received light beam upon the cathode 20 so as to afford increased intensity. It is unnecessary to focus the light beam upon the cathode and therefore the lens L may have a longer focal length than its distance from the cathode 20. As here shown the jack 44 is secured to the bracket d and then passes through the center of the cap 48 which is screw threaded onto the flashlight casing, this structure sufficing to hold the chassis 21 and its brackets 6 in proper position within the tubular casing Z.

The described structural arrangement is of consequence and importance in the original assembly of the receiver and any subsequent disassembly for replacement or repair. As here shown, the photoelectric cell M can readily be removed through the forward end of the flashlight by first removing the lens L. The rear cap 48 is then removed and the chassis 21 is pulled out sufficiently to remove the plug 42 from the jack 43, whereupon the chassis 21 can be removed. It will be noted that no tools are required for this

removal nor for again inserting the parts in assembled position.

As shown in Fig. 1 and Fig. 3 these two flashlight casings Y and Z are connected together by the expandible clamp C which has two interengaging parts 50 and 51 which are slidably engaged with each other. As here shown, the part 51 has a lip 52 on each of its opposite edges and these lips form guideways in which the part 50 is slidably mounted. These slidable parts 50 and 51 are provided with corresponding slots 53 and 54 through which a thumb screw 55 is mounted to hold the parts in set relation.

As best seen in Fig. 3 the part 50 has a curved portion 50' which fits around the tubular casing Z and the part 51 has a curved portion 51' which fits around the tubular casing Y. These curved portions 50' and 51' embrace slightly more than half the circumference of these tubular casings and are sufficiently resilient so that they can be snapped on and off whenever it is desired to separate the transmitter and receiver from each other. These curved portions frictionally engage the tubular casings so that they are longitudinally slidable therein and can readily be brought into the required mouth and ear positions by pushing the transmitter casing Y forwardly and pulling the receiver casing Z rearwardly according to the requirements of the individual operator, and the expandible clamp C enables the two casings Y and Z to be suitably spaced apart in parallel relation, so that when the transmitter is directed towards the receiver of another operator, the transmitter of the latter will also be directed towards the receiver of the former in immediate readiness for two-way communication.

The device is sufficiently small to be readily carried about and can readily be attached to the belt strap of the user. The entire equipment is contained in the two flashlight cases, with the exception of the battery 47 which can conveniently be carried on the belt strap of the user.

In the operation of the invention, the two flashlight cases are spaced apart and slidably moved to the positions shown in Fig. 3 so that the microphone 12 and earphone 39 will be in proper relationship for the mouth and ear of the operator. The battery 47 is plugged in and the operator makes known his intention to communicate by using the switch X to give any suitable flash signal while pointing the transmitter tube towards a second operator with whom he desires to communicate. The second operator then places his photophone in proper mouth and ear positions and answers by using his switch X to give a suitable flash signal. These flash signals afford a convenient guide to enable each operator to properly direct his transmitter merely by pointing it, without resorting to any sighting means. The switch X is kept closed while using the transmitter, and two-way communication is had without resorting to any switching. Each operator may alternately turn towards any other operator and communicate with each of them individually, without being heard by more than one at a time.

It will be seen that the invention provides a compact, lightweight photophone which is very inexpensive and requires no skill to operate.

I claim as my invention:

1. A photophone comprising a tubular flashlight casing having a filament lamp and reflector disposed so as to direct light forwardly in line with the axis of said casing, a microphone on the rear end of said casing, a series of bat-

teries in end-to-end relation within said casing, a transformer within said casing and having its primary in series between said microphone and said batteries and having its secondary in series between said lamp and said batteries, circuit connections including a switch for connecting said batteries to said lamp and said microphone, a second tubular casing having a convex lens in the forward end thereof, a photoelectric cell spaced rearwardly of said lens, an amplifier within said second casing and in circuit with said photoelectric cell, an earphone laterally disposed upon said second casing and in circuit with said amplifier, and means for holding said casings in spaced apart parallel relation with said microphone disposed more forwardly than said earphone.

2. A photophone comprising a pair of tubular casings, an expandible clamp wherein said tubular casings are slidably and rotatably mounted in spaced apart parallel relation, a light projecting transmitter in one of said casings, an amplifying receiver in the other of said casings, said transmitter having its microphone located on the rear end of its casing and said receiver having an earphone mounted on the side of its casing.

3. A photophone comprising a pair of tubular casings, an expandible clamp wherein said tubular casings are slidably and rotatably mounted in spaced apart parallel relation, a microphone mounted on the rear end of one of said tubular casings, a filament lamp and a reflector mounted in the forward end of said casing, a series of batteries arranged in end-to-end relation within said casing, a transformer having its primary coil connected in series between said microphone and said batteries and having its secondary coil connected in series between said lamp and said batteries, a switch for connecting said batteries to said lamp and said microphone, a photoelectric cell mounted in the forward end of the other of said tubular casings, a lens for condensing light upon said photoelectric cell, an amplifier mounted within the latter casing and in circuit with said photoelectric cell, an earphone in circuit with said amplifier, and a jack in the rear end of the latter casing for connecting said amplifier to a power supply.

4. In a photophone, a transmitter comprising a tubular casing, a single button carbon granule microphone mounted on one end of said casing, a filament lamp mounted at the opposite end of said casing, a series of batteries disposed in end-to-end relation within said casing, a transformer within said casing, said transformer having its primary directly connected in series between said microphone and said batteries, said transformer having its secondary directly connected in series between said lamp and said batteries, said lamp and said microphone being connected to a common ground, a switch mounted on said casing and connecting said batteries to the common ground, said lamp having a reflector directing the light outwardly along the axis line of said tubular casing.

5. In a photophone, a transmitter comprising a tubular flashlight casing having a filament lamp and a reflector axially disposed therein, a transformer mounted behind said lamp and having its secondary connected thereto, a disc having a central contact button connected in common to the primary and secondary of said transformer, a series of batteries arranged in end-to-end relation within said casing and having a contact

with said button, a spring mounted on an insulator and contacting the outermost battery, a central contact button on said insulator and connected to the primary of said transformer, a single button carbon granule microphone mounted on the rear of said casing and contacting the last said central contact button, said microphone and said lamp having a common ground, and a switch connecting said spring to the common ground.
